CARBURETOR

Charles R. Snyder, Miami Beach, Fla.

Application July 26, 1939, Serial No. 286,696

13 Claims. (Cl. 261—88)

This invention relates to improvements in carburetors of the type employed for producing vaporized or gaseous fuel mixtures for internal combustion engines.

5 Certain general objects of the invention reside in the provision of a novel carburetor wherein the carburetted fuel mixture produced thereby will be of an efficient and uniform character at all speeds of engine operation, in order to enable 10 an engine to operate with greater smoothness, flexibility and fuel economy than are obtainable with carburetors of more conventional design; and in the provision of a carburetor characterized by the simplicity of its mechanical construction 15 and accessibility of its internal mechanisms.

It is another object of the invention to provide a carburetor having a rotary impeller, or other equivalent means, by which liquid fuel delivered to the impeller is disseminated in a confined 20 chamber in the form of a fine mist or spray, and through which spray, air is passed in intimate combining and vaporizing contact with the finely dispersed particles of the impeller discharge spray, so that there is produced a resulting fuel 25 mixture of a more completely vaporized character than is obtainable with ordinary carburetors, and one which may be more economically and efficiently utilized as an explosive mixture in the cylinders of an associated engine.

30 The present application is a continuation in part of my prior application, Serial No. 119,477 filed January 7, 1937 (allowed April 10, 1939 and abandoned by failure to pay final fee).

For a further understanding of the invention, 35 reference is to be had to the following description and the accompanying drawings, wherein:

Fig. 1 is a vertical sectional view taken through a carburetor constructed in accordance with the present invention;

40 Fig. 2 is a top plan view of my improved carburetor;

Fig. 3 is a detail side elevational view of the air shutter control mechanism;

Fig. 4 is a detail vertical sectional view on the 45 plane indicated by the line IV—IV of Fig. 1;

Fig. 5 is a similar view on the plane disclosed by the line V—V of Fig. 1;

Fig. 6 is a horizontal view on the line VI—VI of Fig. 1;

50 Fig. 7 is a horizontal sectional view taken through the rotary impeller or turbine on the line VII—VII of Fig. 1.

Referring more particularly to the drawings, the numeral 1 designates the casing of my improved carburetor. In this instance, the casing

comprises circular upper and lower plates 2 and 3, respectively, the said plates being spaced by a ring or annulus 4, which may be of a transparent or translucent material so that the mechanism arranged within the mixing chamber 5 of the carburetor may be observed from the exterior. Other materials of course may be used in the construction of the ring or annulus without departing from the invention.

5 Formed with the upper plate 2 is an air admitting conduit 6, the latter being curved or bent to form an elbow 7 which arises from the plate 2 and terminates in a laterally directed and upwardly projecting extension 8.

10 In this extension, there is disposed a pair of 15 air-admitting shutters, as indicated at 9 and 10. Normally, these shutters are disposed in the horizontal positions indicated in Fig. 1, obstructing air flow into the conduit 6, the adjoining edges of 20 said shutters being separated by a thin stationary divider wall 11, which projects a short distance downwardly into the extension 8.

25 The shutter 9, substantially rectangular in configuration, is connected along one edge with a rock shaft 12, journaled for rotation in the walls 25 of the extension 8. One end of the shaft 12 projects exteriorly of the extension 8 and has fixed thereto a crank arm 13, by which the rock shaft is partially rotated. The outer end of the crank 30 arm 13 is pivotally connected as at 14 with one end of a link 15. The other end of this link, as shown in Fig. 3, is slotted as at 16 for the reception of a pin 17 projecting from the outer end of a crank arm 18 which is fixed upon the outer 35 end of a second rock shaft 19, employed in effecting the support of the air shutter 10.

40 The crank arm 18 is considerably shorter than the crank arm 13 so that when a partial vacuum exists in the chamber 5, the pressure of atmospheric air on the shutters 9 and 10 will cause the latter to oscillate about the axes of the rock shafts 12 and 19. The movement of the air shutter 10, however, is greater or faster than that of the shutter 9. These shutters operate as individual 45 valves, as the divider 11 separates the same and provides two parallel paths of air travel.

45 These air shutters or valves are linked together by the link 15 and the crank arms 13 and 18, with the leverage so distributed that the shutter 50 10 will travel at a speed much faster than the shutter 9. Further, provision is made in the linkage, by use of the slot 16, so that when the valve 10 travels its full 90 degrees of movement and comes to rest in a fully opened position, the link- 55

age fails to act as a stop in arresting the travel of the second shutter 9, which will have traveled but a part of its full radius of travel due to the air pressure on it and also to the leverage pull imparted by the shutter 10.

As the air volume increases, the shutter 10 remains open, with the shutter 9 continuing to move toward its open position. Due to the short length of the crank arm 18, the air pressure required to swing the shutter 10 into operation or open position is much less than that required on the other shutter, with the result that the shutter 10 will complete its full travel and, as the air pressure continues to increase, the second valve 15 will pick up from that point and open until the maximum opening of both shutters is reached. The shutter 9, as will be hereinafter explained, is connected to the gasoline flow controlling needle valve to govern its operation, while the shutter 20 10 only indirectly operates in controlling the needle valve through the linkage joining the shutters 9 and 10. By the construction disclosed, the shutters are linked together in such manner that one will open at a time to its fully opened position, the operation of the other being related, pending a greater demand for air inflow into the carburetor.

In Fig. 3, there has been disclosed a pivoted arm 20. This arm is joined with a wire 21 or other flexible cable leading to an operator's position. By applying a pulling force to the wire 21, the foot 22 of the arm 20 will engage with the crank arm 13, thus causing the oscillation of the rock shaft 12 and the manual actuation 35 of the fuel control valve of the carburetor. While a manual "choke" control has been disclosed, it will be understood that the conventional thermostat control may be employed with equal facility.

40 In order to coordinate the inflow of liquid fuel into the carburetor with the inflow of air, the rock shaft 12 is provided with an upstanding ear 23, to the upper portion of which is connected one end of a link 24. The other end of this link 45 is connected with an L-shaped lever 25. Thus lever is provided, as shown in Fig. 4, with fulcrum trunnions 26, the ends of the trunnions being journaled as at 27 in a ring 28. This ring engages with a flexible diaphragm 29, which closes 50 or seals the open side 30 of a drum-shaped housing 31. The opposite side of the housing 31 is closed by a removable plate 32, and a fuel pipe line 33 having a threaded fitting 34 enters the housing axially through the plate 32. The pipe 55 line 33, of course, leads from any suitable source of liquid fuel supply, but preferably from a source of fluid under pressure as a fuel pump although the device will operate when fed from an elevated tank. The ring 28 is securely united with the diaphragm 29 and the walls of the housing 31 by screws 35, producing a fluid tight connection or seal.

The horizontal arm of the lever 25 extends axially into the interior of the housing 31, passing through the central portion of the diaphragm 29 and to which the lever 25 is securely clamped by the use of a nut 36. Due to its flexibility, the diaphragm 29 permits of limited oscillation of the lever 25 and at the same time seals the 65 interior of the housing 31 against liquid loss. The provision of the diaphragm 29 thus obviates the necessity for employing the usual objectionable stuffing boxes or packing glands.

70 The upper end of the lever 25 is connected with one end of a coil spring 37. The other end

of the coil spring is joined with an adjustable bolt 38, mounted with the plate 32 of the housing 31. The spring 37 thus serves in the dual capacity of yieldably maintaining the lever 25 and the shutters 9 and 10 in their normal positions, and 5 regulating the proportion of fuel and air introduced into the mixing chamber.

The inner end of the lever 25 is slotted as at 40 for the reception of a pin 41 carried by the upper end of the stem 42 of a vertically guided 10 needle valve 43. The valve and its stem are arranged in the vertical passage 44 provided in a tubular member 45. This member is positioned snugly within a tubular boss 46 integrally depending from the elbow 7 of the air conduit 6. 15 Toward its lower end, the tubular member is externally threaded, as at 47, for the reception of a nut 48 which, when tightened, holds a frusto-conical air deflecting plate 49 in its stationary operative position. In this connection, and by 20 reference to Fig. 1, it will be noted that the outer peripheral portion of the plate 49 is slightly spaced from the lower annular edge of the elbow 7, producing a restricted annular space 50 for the flow of air leaving the open lower end 25 of said elbow.

The extreme lower end of the tubular member 45 is internally threaded for the reception of a seating guide 51. This guide extends upwardly into the internal passage of the tubular member 30 and is formed at its upper end with a drilled head 52 for the slidable reception of the stem of the needle valve. The head 52 also acts as an abutment for one end of a coil spring 53. This spring surrounds the valve stem below the head 35 52, and the lower end of the spring presses against a collar 54 which is fixed on the valve stem immediately above the conical tapered extremity 55 of said needle valve. Thus the tendency of the spring 53 is to maintain the tapered 40 end 55 of the needle valve in contact with the correspondingly tapered and small seating orifice 56, formed axially in the lower end of the guide 51. This guide is slotted along its sides and through the head 52 so that liquid fuel may 45 readily pass through and around the same toward the orifice 56.

Also, the lower end of the guide includes an annular flange 57 which acts as a seat for the inner race 58 of a ball thrust bearing. The outer race 59 of this bearing is firmly forced into a hub 60 depending from the rotary impeller 61. This impeller, as shown in Figs. 1 and 7, includes radial vanes 62 which communicate at their inner ends with the annular space 50, so that air 55 drawn into the carburetor through the conduit 6 will strike the vanes while moving at high velocity, causing high speed rotation of the turbine or impeller in order to effect the centrifugal dissemination of the liquid fuel discharged in regulated quantities through the orifice 56. Connected with a flange 63, forming a part of the hub 60, is a disk-shaped disseminator 64, the latter being united with the flange 63 by means of the threaded pins 65.

It will be seen that as air is drawn into the carburetor through the shutters 9 and 10, it is caused to travel at high velocity through the space 50, when it contacts with the vanes 62, producing high speed rotation of the air turbine or impeller 61. Corresponding high speed rotation is thus imparted to the disseminator 64 as it is directly connected with the under part of the impeller or turbine. Thus, liquid fuel, discharged from the orifice 56, is first deposited 70 75

upon the central portion of the disk-shaped disseminator, where it is subject to centrifugal forces, caused by the rapid rotation of the disseminator. As a result, the fuel is discharged from all portions of the outer peripheral edge of the disseminator in the form of a fine mist of annular configuration. Air, discharged from the outer portions of the turbine or impeller, is drawn downwardly through this mist and intimately combines with the liquid fuel particles to produce an efficient vaporous or gaseous mixture by the turbulence thus set up. If the air space 58 becomes too small to provide for the air inflow into the carburetor, provision is made 10 to cause the air to partially by-pass the turbine or impeller.

Thus, as shown in Figs. 1 and 6, the lower end of the elbow 1, above the impeller, is formed with arcuate ports 66. These ports are normally 20 closed by arcuate shutters 67, which are hingedly mounted as at 68. The shutters 67 are kept normally closed by means of springs 69. These shutters will open in response to high air pressures, permitting a portion of the air entering the carburetor to by-pass the impeller or turbine 61. The operation of the shutters 67, however, is such as not to in any way interfere with the desired flow of air through the impeller to cause the high speed rotation at any stage of carburetting operation. The disseminator disk 64 is somewhat smaller in diameter than the impeller 61. These proportions are provided in order that there will be no interference with the discharge of liquid fuel in spray form from the peripheral edge of 35 the flat surfaced disk 64 as a result of air flow through the carburetor.

Also, for this reason, a stationary deflector plate 70 is arranged below the disk 64, so that the flow of air through the carburetor will be in 40 the paths indicated by the arrows in Fig. 1. The lower plate of the disk 64 includes a depending tubular extension 71 in which is provided the conventional butterfly valve 72, the latter being carried by a transverse shaft journaled in the extensions 71. The lower portion of the extension 71 terminates in a flange by which the carburetor may be attached to an engine intake manifold, not shown. Standard controls, such as a crank arm and rod extending to the accelerator control 45 of the vehicle, may be employed for actuating the butterfly valve 72.

Entering the extension 71 below the butterfly valve 72 is a threaded fitting 73 of a small copper pipe line 74. This pipe line passes, as 55 shown in Figs. 2 and 4 to a cylinder 75, mounted on the ring 28 of the housing 31. Within the cylinder 75 there is provided a sliding piston 76. This piston is connected at one end with a swinging arm 77 which is pivotally mounted as at 78 60 on the ring 28. The arm 77 carries an adjustable stop in the form of a screw of the type indicated at 79. A small coil spring 80 is connected at one end with the screws 79 and at its other end with the ring 28. A stop pin 81 may be used 65 for limiting the swinging movement of the arm 77 in an outward direction so that the lower end of the screw 79 is removed from engagement with the horizontal portion of the L-shaped lever 25.

By the use of this construction, when the engine 70 associated with the carburetor is started, a partial vacuum is set up in the extension 71, which is transmitted through the pipe line 74 to the cylinder 75, drawing the piston 76 inwardly, and moving the arm 77 against the resistance of the spring 80, so that the lower end of the screw 79

will be positioned immediately over the horizontal branch of the lever 25, thus holding the lever 25 so that the needle valve will be prevented from completely seating in the orifice 56. This provides for the idling of the engine without undue stoppage. However, when the engine is stopped, the vacuum in the cylinder 75 is released, so that the piston 76 and the arm 77 will respond to the influence of the spring 80, moving the set screw 79 to the position disclosed in Fig. 4, thus providing for complete setting of the needle valve in the orifice 56.

In view of the foregoing, it is seen that the present invention provides a carburetor wherein first of all a very intimate contact is effected between the liquid fuel and the oxygen of the air, in order to produce a highly efficient carburetted mixture which will burn cleanly and completely in the cylinders of an associated engine to produce smooth even power. The carburetor is particularly sensitive in its response to changing conditions and very little power is required to effect the operation of its movable parts.

The diaphragm 29 acts as a seal, providing for 25 positive transmission of motion from one gaseous or liquid condition to another different liquid or gaseous condition with virtually no interference or intermingling of one with the other. This transmission of power through the diaphragm is 30 also positive with minimum loss or resistance offered by the seal, due to the differentiation of pressures of the gaseous or liquid fluids on either side of the seal. This minimum resistance is secured by virtue of the pressure being unable to 35 detrimentally affect the linked arms at any point except the fulcrum of the same, where, of course, the pressure is minimized to such an extent as to be scarcely appreciable.

The construction of the carburetor is such as to 40 maintain automatically the desired proportions of the liquid fuel and air in the carburetted mixture at all stages of carburetion. Such proportioning of the fuel mixture is obtained by the operation of the air admitting shutters 9 and 10 and the associated linkage employed which is 45 responsive to the operation of the shutters to govern the degree of opening of the needle valve and consequently the volume or quantity of liquid fuel delivered to the disseminating disk. The spring 50 actuated by-pass shutters 67 are also important in maintaining required volumetric flow of air through the mixing chamber of the carburetor, the said by-pass shutters preventing throttling 55 of the air in the region of the turbine entrance.

A relief valve has been disclosed at 82 in the upper plate 2 of the casing 1 in order to relieve the interior of the carburetor of excessive pressures, such as those which may be produced by 60 engine back-firing.

While I have described the preferred form of the present invention, nevertheless it will be understood that the same is subject to considerable modification without departing from the intent and spirit of the invention as set forth in the 65 following claims.

I claim:

1. In a carburetor of the type having a casing formed to include a mixing chamber provided with air inlet and carburetted fuel outlet passages and fuel disseminating means positioned in the mixing chamber, a fuel conductor tube extending into said mixing chamber and terminating adjacent said disseminating means, valve means in said tube for controlling the flow of 70

fuel from said conductor to said means, a drum-shaped fuel receiver communicating with said fuel conductor, said receiver having an open side, a flexible diaphragm closing the open side of said receiver, a valve actuating lever extending through said diaphragm and connected at its inner end with said valve means, said lever being pivotally supported by said receiver adjacent said diaphragm, the latter being clamped to said lever and serving to prevent the escape of fuel therearound, a normally closed pivoted shutter positioned in said air inlet passage, and linkage means connecting said shutter and the outer end of said lever to impart movement to the lever to 15 actuate said valve upon movement of said shutter in response to the passage of air through the air inlet passage.

2. In a carburetor of the type having a casting formed to include a mixing chamber provided with air inlet and carburetted fuel outlet passages and fuel disseminating means positioned in the mixing chamber, a fuel conductor tube extending into said mixing chamber and terminating adjacent said disseminating means, 20 valve means in said tube for controlling the flow of fuel from said conductor to said means, a drum-shaped fuel receiver communicating with said fuel conductor, said receiver having an open side, a flexible diaphragm closing the open side of said receiver, a valve actuating lever extending through said diaphragm and connected at its inner end with said valve means, said lever being pivotally supported by said receiver adjacent said diaphragm, the latter being clamped to said lever and serving to prevent the 25 escape of fuel therearound, a transversely extending partition wall positioned in said air inlet passage to divide it into a plurality of branches, a normally closed shutter mounted 30 for pivotal movement in each branch and operated by the passage of air therethrough, connecting means between said shutters to control the degree of relative movement therebetween, and linkage means extending between one of 35 said shutters and the outer end of said valve actuating lever to transmit movement to said valve in response to movement of said shutter.

3. In a carburetor of the type having a casting formed to include a mixing chamber provided with air inlet and carburetted fuel outlet passages and fuel disseminating means positioned in the mixing chamber, a fuel conductor tube extending into said mixing chamber and terminating adjacent said disseminating means, 40 valve means in said tube for controlling the flow of fuel from said conductor to said disseminating means, a drum-shaped fuel receiver communicating with said fuel conductor, said receiver having an open side, a flexible diaphragm closing the open side of said receiver, a valve actuating lever extending through said diaphragm and connected at its inner end with said valve means, said lever being pivotally supported by said receiver adjacent said diaphragm, the latter being clamped to said lever and serving to prevent the 45 escape of fuel therearound, a normally closed pivoted shutter positioned in said air inlet passage, linkage means connecting 50 said shutter and the outer end of said valve actuating lever including an arm mounted for

swinging movement on said receiver, spring means normally tending to hold said arm in an inoperative position, and vacuum operated means for swinging said arm to a position to hold said valve in a partially open position during the operation of an engine to which the carburetor is attached. 5

4. A carburetor comprising a casing having a mixing chamber with air inlet and carburetted fuel outlet conduits communicating therewith, a fuel conductor extending into said mixing chamber, an air driven impeller rotatably supported within said mixing chamber by said fuel conductor, a deflector wall extending across the inner end of said air inlet conduit in the vicinity 10 of said impeller to maintain a substantially uniform flow of air to said impeller, a spring pressed by-pass valve carried by said air inlet conduit in advance of said deflector and within said mixing chamber, a disseminating disk secured for 15 rotation with said impeller, and valve mechanism for controlling the flow of fuel through said conductor to said disk.

5. In a carburetor of the type having a casting provided with a mixing chamber, air inlet and carburetted fuel outlet conduits, fuel vaporizing means supported in the mixing chamber, a fuel conduit extending into the mixing chamber and terminating adjacent said vaporizing means, a hollow liquid fuel receiver communicating with said conduit, said receiver having a circular opening in one side, valve means extending through said conduit and operating to control the flow of fluid therethrough, an operating lever for said valve extending into said receiver through the opening, pivot means for said lever extending diametrically across the opening in said fuel receiver, a diaphragm secured over said opening and to said lever in fluid-tight relationship, the connection between said diaphragm and lever being adjacent said pivot means, the inner end of said lever being operatively connected with said valve means, spring means connected with the outer end of said lever and normally tending to move said valve to a closed position, a shutter pivotally supported in the air inlet conduit for movement in response to the passage of air therethrough, and motion transmitting means between said shutter and said lever for moving the latter in opposition to 30 said spring. 35

6. In a carburetor of the type having a casting provided with a mixing chamber, air inlet and carburetted fuel outlet conduits, fuel vaporizing means supported in the mixing chamber and a fuel conduit extending to the mixing chamber and terminating adjacent said vaporizing means, a hollow liquid fuel receiver communicating with said conduit, said receiver having a circular opening in one side, valve means extending through said conduit and operating to control the flow of fluid therethrough, an operating lever for said valve extending into said receiver through the opening, pivot means for said lever extending diametrically across the opening in said fuel receiver, a diaphragm secured over said opening and to said lever in fluid-tight relationship, the connection between said diaphragm and lever being adjacent said pivot means, the inner end of said lever being operatively connected with said valve means, spring means connected with the outer end of said lever and normally tending to move said valve to a closed position, a partition wall dis- 50 55 60 65 70 75

posed in the air inlet conduit and dividing it into a pair of branches, a transversely extending shaft journaled in each branch adjacent the wall opposite said partition wall, a shutter secured to each shaft and movable therewith in response to the flow of air into said conduit, a crank arm secured to each shaft exteriorly of said conduit, said crank arms being unequal in length, link means connecting said crank arms 5 to provide for simultaneous movement of the shutters, a second crank secured to the shaft having the longer crank arm, and a link extending between said second crank and said valve operating lever to impart movement to said valve 10 in proportion to the movement of the shutter provided with the longer crank arm.

7. In a carburetor of the type having a casing formed to include a mixing chamber provided with air inlet and carburetted fuel outlet passages and fuel vaporizing means positioned in the mixing chamber, a fuel conductor tube extending into said mixing chamber and terminating adjacent said vaporizing means, valve means in said tube for controlling the flow of 15 fuel from said conductor to said vaporizing means, partition means positioned in the air inlet passage to divide it into a plurality of inlet branches, a normally closed pivoted shutter positioned in each branch, and operated by the 20 passage of air therethrough, means for connecting said shutters to control the degree of relative opening movement thereof, motion transmitting mechanism connecting one of said shutters with said valve means to impart movement 25 to the latter when the former moves in response to the passage of air through the air inlet passage, and means for operating said fuel control valve independently of the flow of air through the air inlet passage.

40 8. In a carburetor, a casing provided with a mixing chamber and inlet and outlet passages communicating therewith, a tubular fuel conducting member projecting through said inlet passage and into said chamber, a plug provided 45 with a reduced bore positioned in the inner end of said tube, a needle valve movably positioned in said tube and cooperating with said plug to control fluid flow through said tube, a lever pivotally supported adjacent the outer end of said 50 tube, an air actuated member positioned in said inlet passage, connections between said member, said needle valve and the ends of said pivoted lever to actuate said valve in response to the movement of air through said inlet passage, an 55 impeller having a plurality of radiating passages disposed in a plane at right angles to the axis of said chamber rotatably secured to the inner end of said tubular member, the inner ends of the radiating passages communicating with the 60 inlet to said chamber, and a disk positioned adjacent the inner end of said tubular member and secured for rotation with said impeller.

9. A carburetor for internal combustion engines comprising a casing having a mixing chamber, an air admitting conduit of smaller diameter than said chamber entering one side of the latter, a carburetted fuel discharge conduit of smaller diameter than said chamber communicating with the opposite side of the latter, a 65 fuel admitting pipe carried by said casing and terminating axially within said chamber, valve means responsive to the passage of air through said air admitting conduit for controlling the passage of fuel through said pipe, a rotatable 70 fuel disseminating disk having a substantially 75

flat surface on which liquid fuel discharged from said pipe is deposited, an air driven rotor of greater diameter than said disk for revolving the latter, said rotor comprising a pair of horizontally arranged spaced plates having turbine 5 blades disposed between the same, one of said plates being in open registration with the discharge end of the air admitting conduit, whereby air drawn through said last-named conduit into said chamber engages the blades of the rotor 10 to revolve the latter about the axis of said pipe connection, the rotation of said rotor and disk causing liquid fuel deposited on the disk to be discharged in finely divided spray form in a substantially horizontal plane from the entire periphery of said disk for intimate contact with air passing through the mixing chamber in a direction generally perpendicular to the fuel spray, and a stationary baffle of greater diameter than said disk arranged on the opposite side 20 of the latter as regards said rotor, said baffle and said rotor serving to provide a protected area about the peripheral portion of said disk to prevent air currents passing through said mixing chamber from interfering with the radial 25 discharge of the liquid fuel from said disk.

10. In a carburetor, a casing having an enlarged mixing chamber, an air inlet conduit communicating with said chamber, a pivoted damper valve in said air inlet conduit and responsive to the passage of air therethrough, a carburetted fuel conductor leading from said mixing chamber, a smooth flat disk mounted for rotary movement in said chamber, means operated by the passage of air through said chamber to 35 rotate said disk, a fuel feed line entering said chamber, a nozzle provided at the outlet of said fuel line, said nozzle being in registration with the center of rotation of said disk, and a valve for controlling the flow of fuel through said nozzle, said valve being connected and operated in unison with said damper valve.

11. In a carburetor of the type having a mixing chamber and air inlet and carburetted fuel outlet passages communicating therewith, fuel vaporizing means positioned in said mixing chamber comprising an impeller of the centrifugal type rotatably supported in said chamber, said impeller having spaced disks and curved blades positioned therebetween, one of said disks 45 having a central opening in registration with the air inlet passage of said mixing chamber, means disposed in said air inlet passage adjacent the impeller for restricting the flow of air to said impeller, means provided with said air inlet passage in advance of said air restricting means for causing a portion of the air to enter said mixing chamber without passing through said impeller, a fuel vaporising disk supported for rotation with said impeller, and means for introducing liquid fuel in regulated quantities to said disk.

12. In a carburetor of the type having a mixing chamber, a fuel conductor having an opening in one side extending into said chamber and receiving liquid fuel under superatmospheric pressure, means for controlling the flow of fuel from said conductor into said chamber comprising a normally closed valve positioned in said conductor, a lever extending through the opening in the side of said conductor and connecting with said valve member, flexible means closing the opening in the side of said conductor, said flexible means having a fluid-tight connection with said lever and conductor, and means for imparting 65 70 75

motion to said lever to effect movement of said valve.

13. In a carburetor of the type having a mixing chamber, air inlet and carburetted fuel outlet conduits communicating with said chamber, and a throttle valve disposed in said outlet conduit, a fuel conductor having an opening in one side extending into said chamber and receiving liquid fuel under superatmospheric pressure, means for controlling the flow of fuel from said conductor into said chamber comprising a normally closed valve positioned in said conductor, a lever extending through the opening in the

side of said conductor and connecting with said valve member, flexible means closing the opening in the side of said conductor, said flexible means having a fluid-tight connection with said lever and conductor, means for imparting motion to said lever to actuate said valve, and means responsive to negative pressures in said carburetted fuel outlet beyond said throttle valve to resist movement of said lever to retain said valve in a position providing for limited fuel flow into said mixing chamber. 5 10

CHARLES R. SNYDER.
